US00D937287S

(12) **United States Design Patent** (10) **Patent No.:** **US D937,287 S**
Lee et al. (45) **Date of Patent:** **** Nov. 30, 2021**

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Seungjoon Lee**, Suwon-si (KR); **Hyeyoung Jang**, Suwon-si (KR)

(73) Assignee: **SAMSUNG ELECTRONICS CO., LTD.**, Gyeonggi-Do (KR)

(**) Term: **15 Years**

(21) Appl. No.: **29/741,868**

(22) Filed: **Jul. 16, 2020**

(30) **Foreign Application Priority Data**

Apr. 17, 2020 (KR) 30-2020-0017164

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The outermost perimeter illustrated by a pair of dashed broken lines show the display screen or portion thereof and forms no part of the claimed design. The remaining dashed broken lines illustrating portions of the graphical user interface form no part of the claimed design.
